UNITED STATES PATENT OFFICE.

WILLIAM H. B. LAVARACK, OF PINEBUSH, NEW YORK, AND DANIEL W. RICHARDS,
OF ROANOKE, VIRGINIA.

PARKWAY-CABLE TERMINAL.

Application filed September 28, 1926. Serial No. 138,162.

This invention relates to electrical connectors and particularly a connector suitable for use on the end of what is known as a parkway cable.

5 A principal object of this invention is to provide a connector or terminal for a parkway cable, which will be inexpensive to manufacture, easy to install, and when installed will completely protect the end of the parkway cable from the entrance of water or moisture.

Other objects and advantages will appear as the description of the particular physical embodiment, selected to illustrate the invention progresses, and the novel features of the invention will be particularly pointed out in the appended claims.

In describing the invention in detail, and the particular physical embodiment selected 20 to illustrate the invention, reference is had to the accompanying drawing, wherein we have illustrated a particular preferred physical embodiment of our invention, and where like characters of reference designate corresponding parts throughout the several views, and in which:

Figure 1 is a side elevation showing a rail, a parkway cable connected to the rail, and our improved parkway cable terminal in place on the cable; Fig. 2, is a cross sectional view illustrating the internal construction of our improved parkway cable terminal; Fig. 3, is a cross sectional view on the plane indicated by the line III—III of Fig. 2, viewed 35 in the direction of the arrows at the ends of the line; Fig. 4, is a cross sectional view of a modified form of parkway cable terminal made in accordance with our invention; Fig. 5, is a cross sectional view on the plane indicated by the line V—V of Fig. 4, viewed 40 in the direction of the arrows at the ends of the line; Fig. 6, is a sectional view illustrating the construction of a parkway cable.

In the drawings and particularly Fig. 1, 45 the numeral 1 designates an ordinary trackway rail resting on cross ties 2. 3 designates the ordinary and well-known parkway cable which is held rigidly clamped by any of the well-known means, and preferably by clamp 50 4 to the rail 1. T designates generally our improved parkway cable terminal, which is connected by means of the bond wires 5 to the rail 1, by the use of the double grooved channel pin 6.

55 By reference to Fig. 2, it will be seen that

the terminal T, is formed as a somewhat cylindrical body, having a part of major dimension 7 and a part of minor dimension 8. The part of major dimension 7 is provided with a cavity of major dimension 9. Into 60 this cavity, the parkway cable 3 extends, and an insulating washer 40 is interposed between the parkway cable 3 and the bottom of the cavity 9. Applicants also, after placing the parkway cable in the terminal as shown by 65 Fig. 2, with a washer interposed, then run, insulating material 10, around the cable so as to fill all of the interstices between the cable and the terminal T. The insulating washer 40 is placed in the bottom of the 70 cavity, because as shown by Fig. 6, the parkway cable has a central conductor 11, surrounded by various layers of insulating and protecting material. One of these layers 12 is made of metal, and is generally iron or 75 steel ribbon wound about the cable. There is also generally provided a lead sheath 13. In order to prevent the lead sheath and the iron or steel ribbon sheath from touching the metal of the terminal, the insulating 80 washer 40 is used, made of any insulating material, such, for instance, as fiber or hard rubber.

In the form of the terminal as shown by Fig. 2, a cavity 14 of minor dimensions connects with and forms a prolongation of the cavity of major dimension, and in addition two cavities 15 and 16 extend longitudinally of the terminal in the portion of minor dimension at the end of the terminal opposite 90 to that in which the parkway cable is positioned. These three last cavities all open into a transverse cavity 17 formed in the portion of minor dimensions, which cavity 17 may be considered one of intermediate dimensions. Within the cavities 15 and 16, are positioned the bond wires 5 and within the cavity 14 is positioned, conductor 11 of the parkway cable. 95

In order to make a firm and lasting union, 100 and to exclude moisture, the cavity 17, after the conductors 5 and 11 are inserted therein, is filled with a soldering metal such as tin and lead as is usual, which firmly holds the conductors, as 5 and 11, which are of copper, 105 with the terminal T, which we prefer to make of brass.

In Fig. 4, and in cross section in Fig. 5, we have shown a slightly modified form of our terminal, in that the bond wire corre- 110

sponding to the bond wires 5 of Fig. 2, consists of a single conductor 18. It is of course understood that the showing of applicants does not exclude the use by them of park-
5 way cable, consisting of a plurality of wires or a single wire, solid or stranded, or bond wires as 5, single or in multiple, solid or stranded.

Although we have particularly described 10 the construction of physical embodiments of our invention, and explained the operation and principle thereof, nevertheless, we desire to have it understood that the forms selected are merely illustrative, but do not 15 exhaust the possible physical embodiments of the idea of means underlying our invention.

What we claim as new and desire to secure by Letters Patent of the United States, 20 is:

1. In a parkway cable connection, in combination: a parkway cable; a rail; a bond wire electrically connected to the rail and having a free end; a metallic body provided 25 with a cavity in one end; an insulating washer interposed between the cable and the bottom of the cavity; insulating material

filling all interstices between the cable and the walls of the cavity; said body formed with a transverse cavity intermediate its 30 ends and orifices through which the cable and the free end of the bond into the transverse cavity and soldering metal filling the transverse cavity and surrounding the conductor and the bond wire.

2. In a cable connector, in combination: a metallic body formed with a cavity for receiving a cable, an orifice for receiving a conductor of a cable and an orifice for receiving a conductor for electrical connection 40 with the conductor of the cable and an orifice connecting the last two named orifices for receiving a soldering metal.

3. As an article of manufacture a somewhat cylindrical metal body formed with a longitudinal cavity in one end of major dimensions, and a continuation thereof of minor dimensions and a longitudinal cavity of minor dimensions in the other end and a transverse cavity of somewhat intermediate 45 dimensions connecting the last two mentioned cavities.

WILLIAM H. B. LAVARACK.
